UNITED STATES PATENT OFFICE

2,526,580

CONICAL SHADOW BOX DISPLAY

Earl M. Roach, Chicago, Ill., assignor to Arvey Corporation, Chicago, Ill., a corporation of Illinois

Application December 14, 1946, Serial No. 716,246

5 Claims. (Cl. 40—126)

1

This invention relates to improvements in display devices and is more particularly concerned with the provision of a shadow box display adapted to be simply and inexpensively constructed of cardboard, or the like, for use in displaying and advertising various kinds of merchandise.

This invention further contemplates the provision of an improved shadow box display in which an annular frame of angular cross section is adhesively or otherwise attached to the base of a conical body, the frame and body being secured in set-up position by means of interlocking tongues and notches formed on the frame, and collapsible to a flat knock-down form suitable for storage or shipment to a point of use.

This invention further contemplates the provision of a shadow box display in which the annular frame embodies inner and outer annular flanges diverging rearwardly from the base of the conical body, with the inner flange disposed in spaced, substantially parallel relation to the inner side wall of the conical body to thus provide an annular inwardly facing recess from which light rays from a suitable lamp disposed within the recess will be reflected inwardly along the inner surface of the conical body and toward the apex thereof without illuminating the front face of the annular frame. If desired, a lamp may be positioned in front of the display for directing a beam of light toward the front end thereof, to thus illuminate the front face of the annular frame and that portion of the conical body disposed within the inner diameter of the frame, with an annular relatively dark area between the frame and the illuminated portion of the conical body.

This invention embodies other novel features, details of construction and arrangement of parts which are hereinafter set forth in the specification and claims, and illustrated in the accompanying drawings wherein:

Fig. 1 is a front elevational view showing a conical shadow box display embodying features of this invention.

Fig. 2 is a sectional view taken along the line 2—2 of Fig. 1.

Fig. 3 is an enlarged detail sectional view taken along the line 3—3 of Fig. 1.

Fig. 4 is an enlarged detail sectional view taken along the line 4—4 of Fig. 1.

Fig. 5 is a fragmentary detail view illustrating the manner in which the ends of the annular frame are moved toward each other for interlocking engagement.

2

Fig. 6 is a plan view showing a display in its flat collapsed position.

Referring now to the drawings for a better understanding of this invention, the shadow box display is constructed from a disc-shaped blank of cardboard A and an arcuate-shaped blank of cardboard B which are adhesively or otherwise attached to each other at 7 to provide a flat knock-down form, as illustrated in Fig. 6, suitable for storage or shipment to the point of use. The blank A is scored radially at 8, 9 and 10 to permit the blank to be drawn into a conical formation to provide a cone-shaped body 11 for the display.

One end of the blank B is formed with a notch 12 and locking tongues 13 and 14, and the other end of the blank is formed with a notch 16 and a locking tongue 17. The blank B is also scored along a line 18 to provide a frame 19 having an inner flange 21 and an outer flange 22. The blank A is also scored at 23 to provide an attachment flange 24 for adhesive engagement at 7 to the outer flange 22 of the frame 19. A tongue 26 is formed on the blank A at the outer end of the score line 9 for insertion in a slot 27 formed in the blank A.

In setting up the display, the sections 28 and 29 of the blank A defined by the score lines 8, 9 and 10 are caused to move outwardly into side-by-side relation, and is illustrated in Fig. 4, to permit insertion of the tongue 26 through the slot 27. The blank A thus forms a conical body 11 of the display. During the formation of the cone-shaped body 11 the ends of the frame 19 are moved toward each other for interlocking engagement by means of notches 12 and 16 and the tongues 13, 14 and 17. The tongue 17 is adapted to be moved downwardly through a notch 31 while the tongue 13 is disposed against the inner face of the outer annular flange 22. Each locking tongue 13 and 17 is thus disposed against the back face of the annular outer flange 22 and is not visible from the front side of the display. After the ends of the frame 19 have been interlocked by means of the tongues 13 and 17, the tongue 14 is positioned against the front side of the inner annular flange 21. The ends of the frame 19 are also formed with oppositely disposed ears 32 and 33 disposed for overlapping engagement with the ear 32 disposed over the ear 33. After the ends of the frame 19 have been interlocked in the manner shown and described, the tongue 26 on the blank A is inserted through the slot 27 to form an assembled shadow box display.

55 In the use of the display, it is contemplated

that electric lamps (not shown) may be inserted through one or more apertures 34 provided in the cone-shaped body 11. It will be noted that the openings 34 are located to dispose the electric lamps within the annular recess 36 defined by the cone-shaped body 11 and the frame 19. When the electric lamps are connected to a suitable source of current, light is reflected by the walls defining the recess 36 to direct the light beams inwardly along the inner surface of the cone-shaped body 11 and toward the apex thereof. By this means of illumination, the inner surface of the cone-shaped body 11 is brightly illuminated while the outer surface of the annular frame 19 will appear relatively dark.

It is also contemplated that the display may be used with an electric lamp positioned in front of the display to direct light toward the outer surface of the annular frame 19 and the inner surface of the cone-shaped body 11. With this form of illumination, the front face of the annular frame 19 and that portion of the cone-shaped body within the inner diameter of the frame 19 will be brightly illuminated, thereby leaving an annular darkened area within the annular recess 36. Goods on display are positioned in front of and/or around the shadow box.

It will be seen that the blanks A and B forming this display may be inexpensively cut, scored and adhesively united in a flat superimposed relation suitable for shipping and storage. It will further be seen that the display may be erected to its set-up position by merely moving the ends of the frame 19 toward each other for interlocking engagement. It will further be noted that the sections 28 and 29 of the body blank A may be omitted, if desired, to provide overlapping edges 8 and 10 having one or more sets of interlocking fingers of the type formed on the frame at 13 and 17.

While this invention has been shown in but one form, it is obvious to those skilled in the art that it is not so limited but is susceptible of various changes and modifications without departing from the spirit and scope of the claimed invention.

I claim as my invention:

1. A shadow box display comprising, a hollow cone and an annular frame therefor of V-shaped transverse section embracing the circular edge of said cone, one of the legs of said frame overlying said edge in angular relationship thereto and projecting both rearwardly and forwardly thereof, and the other leg projecting inwardly of the cone in spaced relationship thereto providing an annular recess between the wall of the cone and the legs of said frame.

2. A shadow box display comprising, a hollow cone, an inclined annular flange extending outwardly and rearwardly from the circular base edge of the cone, and an annular frame of V-shaped transverse section embracing said circular edge, one of the legs of said frame overlying said flange and said edge and projecting forwardly of the latter, and the other leg projecting inwardly of said cone in spaced substantially parallel relationship thereto providing an annular recess between the wall of the cone and the legs of said frame.

3. A collapsible shadow box display comprising, a normally flat blank cut, scored and foldable to form a hollow conical body, an arcuate normally flat blank cut, scored and foldable to form

an annular frame of V-shaped transverse section for embracing the circular edge of said conical body, means extending from said circular edge forming portions of said body blank for securing one leg of said arcuate blank in overlying relationship to said edge, and interlocking means on the opposed ends of said arcuate blank securing the frame in annular set-up position and for retaining the body blank in conical form with one of the legs of the frame overlying said circular edge in angular relationship thereto and projecting both rearwardly and forwardly thereof and with the other leg projecting inwardly of the cone in spaced relationship thereto to provide an annular recess between the wall of the cone and the legs of the frame.

4. A collapsible shadow box display comprising, a normally flat blank cut, scored and foldable to form a hollow conical body and an integral outwardly and rearwardly inclined annular flange, and a second normally flat blank cut, scored and foldable to form an annular frame of V-shaped transverse section, one of the leg components of said frame being in partial overlying relationship to said flange and secured thereto, and interlocking means on the opposed ends of said second blank for holding the display in set-up position with said partially overlying frame leg projecting forwardly of the circular edge portion of the cone and the other leg projecting inwardly of and in spaced relationship to the cone providing an annular recess between the wall of the cone and the legs of the frame.

5. A collapsible shadow box display of foldable material comprising, a normally flat disc-shaped body blank including an arcuate flange defined therefrom by a score line, said body blank being formed with radial score lines between said flange to define a pair of sectors foldable against each other and to permit said blank to be shaped to the form of a hollow cone with its flange projecting at a rearward incline from the resulting circular edge of the cone, an arcuate normally flat blank divided by an arcuate score line to define two legs, one of said legs overlying said disc and the other overlying said disc and its flange and secured to the latter, and interlocking means at the opposed ends of said arcuate blank for setting up said display and for bringing said arcuate blank to the form of an annular frame of V-shaped transverse section embracing the circular edge of the cone with one of the legs of said frame overlying said edge in angular relationship thereto and with the other leg projecting inwardly of said cone in spaced substantially parallel relationship thereto providing an annular recess between the wall of the cone and the legs of the frame.

EARL M. ROACH.
